ALBERT S. WEBSTER, OF OTTAWA, ONTARIO, CANADA, ASSIGNOR TO AMERICAN BANK
NOTE COMPANY, OF NEW YORK, N. Y., A CORPORATION OF NEW YORK

ROTARY WEB UNDERSURFACE PRINTING MACHINE

Application filed December 30, 1930. Serial No. 505,620.

My invention relates to rotary web undersurface printing machines, and more particularly to a construction by which great accuracy in the relative position of each plate 5 upon a plate cylinder and the makeready of the impression cylinder or D-roll is assured with the initiation of the making of each impression.

In printing machines of the type to which 10 the invention relates, the plate cylinder has a plurality of plates, usually three in number, mounted in spaced relation to each other thereon, and the impression cylinder or D-roll is of a diameter to have one full revolution for each plate upon the plate cylinder.

A continuous web is threaded from a supply reel mechanism between the plate cylinder and the impression cylinder or D-roll to a collecting mechanism, the web being drawn 20 with a step by step movement from the supply reel as a result of clamping action or frictional engagement of the web between a plate upon the plate cylinder and the makeready blanket upon the impression cylinder or D-roll, so that as a plate passes from engaging 25 relation with the impression cylinder or D-roll, feeding movement of the web instantly ceases, and it remains stationary until the succeeding plate approaches and engages the impression cylinder or D-roll, or the web positioned between same.

In order to assure the making of uniformly good impressions, it is customary to impart movement to the impression cylinder or D-roll from the plate cylinder by what is known 35 as a "floating rack" structure carried by the plate cylinder and operative upon a continuous gear upon the impression cylinder or D-roll. This floating rack structure, briefly, 40 consists of a short rack, or starting, segment fixedly connected with the plate cylinder gear, and a floating rack section or one which is movably mounted upon the plate cylinder gear and is acted upon by a spring to normally 45 maintain it in the proper relation to the starting section of the floating rack structure. There is one floating rack structure for each plate upon the plate cylinder, and each structure is of a length to ensure one complete revolution 50 of the impression cylinder or D-roll.

This floating rack section permits minute variations in the angular speed of the impression cylinder or D-roll, due to irregularities in the height of different portions of the plate or of the makeready of the impression 55 cylinder or D-roll, securing much the same effect as would be secured by a loose enmeshment of the teeth of the gears upon the plate cylinder and the impression cylinder or D- 60 roll respectively.

This condition may result in a slight loss of the proper adjustment of the relation of the plates upon the plate cylinder and the impression cylinder or D-roll during any 65 non-printing interval of the machine, or during that interval when the plate upon the plate cylinder is not engaged with the impression cylinder or D-roll.

In the machine of the invention, when printing upon a continuous web in a steel plate printing machine, the impression cylinder or D-roll is accurately positioned with relation to each plate upon the initiation of each printing interval, and whether the full friction drive of the impression cylinder or 70 D-roll is secured by looseness between the gears upon the two cylinders, or by means of a floating rack structure, or by both, the impression cylinder or D-roll mechanism controlling the movement between impressions 75 is so controlled by the plate cylinder as to accurately position said impression cylinder or D-roll with relation to the succeeding plate. It is merely necessary to ensure accuracy in the movements and position 80 of the D-roll immediately following the completion of the making of each impression, and immediately prior to the making of a succeeding impression. By thus placing the impression cylinder or D-roll under the positive control of the plate cylinder, I secure 85 the effect of a continued perfect enmeshment of the impression cylinder or D-roll gear and the gear driving same during that interval between the making of impressions, 90 which is the only interval during which it is desirable to place the impression cylinder or D-roll under the positive control of the plate cylinder gear.

Ordinarily, a floating rack structure is em- 95

ployed in a machine of the type to which my invention relates, and the placing of the impression cylinder or D-roll under the control of the plate cylinder in the manner above 5 described, ensures, following the making of each impression, the immediate restoration of the floating rack section to a position where it will be properly enmeshed with the teeth of the starting section, thus minimizing 10 wear and consequent lost motion resulting from an improper enmeshment of said gear and said starting rack section. Furthermore, said mechanism ensures a positive control of the impression cylinder or D-roll, 15 upon its initial engagement with the floating rack section operative in relation to each plate, as said plate reaches the initial printing position. It ensures a more uniform actuation of the impression cylinder or D- roll; avoids excessive wear at vital points 20 in the gears between said cylinder and the plate cylinder; avoids the necessity for great nicety in the laying out and making of such gearing, and permits the continued uniform 25 operation of the machine notwithstanding wear of such gearing.

It is desirable to provide in the mechanism of the invention, a construction permitting adjustment of the members operative 30 upon the impression cylinder or D-roll in order to permit nicety in the setting of this mechanism with relation to the gearing.

The mechanism of the invention results in extreme accuracy in the positioning of succeeding 35 impressions upon the web and contributes toward high efficiency in the operation of the printing machine embodying same, both as to the quantity and quality of the work produced.

40 The invention consists primarily in a rotary web undersurface printing machine embodying therein a printing couple consisting of an impression cylinder or D-roll, a plate cylinder adapted to receive a plurality 45 of plates in spaced relation to each other, co-operating gears upon said impression cylinder or D-roll and upon said plate cylinder, said gears permitting slight variation in the angular speed of said impression cylinder or D-roll during the making of an impression, and co-operating means carried by 50 said impression cylinder or D-roll and by said plate cylinder, whereby the impression cylinder or D-roll is brought into a definite 55 relation to the plate cylinder upon the completion of the making of each impression and immediately prior to the initiation of the making of the succeeding impression; and in 60 such other novel features of construction and combination of parts as are hereinafter set forth and described, and more particularly pointed out in the claims hereto appended.

Referring to the drawing,

65 Fig. 1 is an end view of a printing couple

of a rotary web undersurface printing machine embodying the invention;

Fig. 2 is a side view thereof, partly in section; and

Fig. 3 is a view upon a larger scale of a 70 fragmentary portion of the members of the printing couple showing one pair of socket plates and the co-operating studs in the position just prior to the engagement of the starting plate with a stud.

75 Like numerals refer to like parts throughout the several views.

In the embodiment of the invention shown in the drawing, a plate cylinder 10 is shown, which cylinder is adapted to have three engraved, intaglio or undersurface steel plates mounted thereon. These plates are indicated at 11, 12 and 13 respectively and are in spaced 80 relation to each other, the gap between succeeding plates being indicated at 14, 15 and 16.

Associated with the plate cylinder 10 is an impression cylinder or D-roll 17 of the usual construction having a recessed portion indicated in dotted lines at 18 interrupting the continuity of the perimeter of this cylinder and receiving the various blanket mounting and adjusting mechanisms.

The plate cylinder 10 is provided with a main gear 19 through which power is applied 95 to the members 10 and 17 of the printing couple. This gear 19 has associated therewith an impression cylinder or D-roll driving gear 20, which may be of the floating rack construction, or may have a loose fit with the gear 21 carried by the impression cylinder or D-roll 17. Ordinarily a floating rack construction is used since such a construction 100 permits a full friction drive of the impression cylinder or D-roll 17 during the making of an impression and affords an ample range of variation in the angular speed of said impression cylinder or D-roll to compensate for irregularities in the plate. The same result, 105 however, can be secured, but less perfectly, by a loose mesh between the gears 20 and 21. Looseness in the gears 20 and 21 is not desirable, since this arrangement sacrifices that accuracy in the operation of the members of 110 the printing couple which is desirable with high class work. Looseness, however, will develop from wear, whether a continuous rack or a floating rack structure 20 is employed, and this looseness introduces the problem 115 solved by my present invention.

120 Since, during the making of the impression, the impression cylinder or D-roll is frictionally driven, and during such interval is under the control of a plate, no difficulties 125 arise as a result of back lash or looseness in the gears 20 and 21 during the making of an impression. It is desirable, however, that the same portion of the makeready of the cylinder 17 be engaged with each plate upon 130

the plate cylinder upon each revolution of the printing couple.

To secure the desired results, I provide the arbor 22 of the impression cylinder or D-roll 17 with a wheel 23 having mounted thereon plates 24 and 25, respectively carrying studs 26 and 27 which are preferably provided with an anti-friction sleeve. These plates 24 and 25 are adjustably mounted by means of set screws 28 in slots 29 upon the wheel 23 to facilitate accuracy in the location of the studs 26 and 27 with relation to co-operating means carried by the gear 20 of the plate cylinder 10.

The diameter of the wheel 23 is greater than that of the gear 21, adjacent which it is positioned, but from which it is spaced in order to position the studs outside of the gear 20. Consequently, the wheel 23 overlays or laps the gear 20.

Carried by the gear 19 is a ring 30 having secured thereto a plurality of pairs of socket plates corresponding in number with the engraved steel plates carried by the plate cylinder 10. One of the plates of each pair is located adjacent the rear end of one plate, and the other plate of each pair is located adjacent the forward edge of the succeeding plate.

In the drawings, the plates of one pair are indicated at 31 and 32, the plates of the succeeding pair at 33 and 34 and the plates of the remaining pair at 35 and 36. The plates 31, 33 and 35 are each located adjacent the rear edge of a printing plate, while the plates 32, 34 and 36 are each located adjacent the forward edge of a printing plate. For convenience of expression, the plates 31, 33 and 35 will be designated stop plates, while the plates 32, 34 and 36 will be designated starting plates. The plates of each pair are spaced apart the same number of degrees in arc as the studs 26 and 27.

Each of the plates 31 to 36 is provided with a socket such as 37, adapted to receive a stud 26 or 27 upon the wheel 23, the mouth of this socket being outwardly flared as shown so as to permit the free engagement and disengagement of the stud with the socket and limit the corrective effect of the co-operating plate and stud to a substantially momentary action when the plate is at substantially the top vertical center of the gear, and the co-operating stud is at substantially the bottom vertical center of the wheel 23.

The various plates 31 to 36 are adjustably mounted by means of the segmental slots 38 and the bolts 39 upon the ring 30.

It will be noted that the studs 26 and 27 are located upon opposite sides of the recess 18, the entire double corrective action occurring while this recess is presented toward the plate cylinder 10.

The operation of the herein described device is substantially as follows:—

In the operation of the machine, the gears 19, 20 and 21 have continuous, uni-directional movement, the gear 21, during the making of an impression, being turned as a result of the frictional engagement of the paper web between the makeready of the cylinder 17 and the plates 11, 12 or 13 upon the cylinder 10, either as a result of the loose enmeshment of the gears 20 and 21, or the use of the floating rack structure herein referred to which forms no part of the present invention. It is merely necessary that the gears 20 and 21 shall be capable of minute variable movement.

Assuming the parts to be in the position shown in Fig. 1, the stud 27 is positioned in the socket 37 of the plate 32 in a manner to ensure a certain predetermined position of the makeready of the cylinder 17 with relation to the plate 11. It will be noted that the axis of the stud 27 is in substantial alinement with the teeth of the gear 21, notwithstanding that the diameter of the wheel 23 is greater than that of said gear.

With the continued rotation of the gears 19, 20 and 21, the latter being under the control of the wheel 23, the makeready upon the cylinder 17 passes into operative relation with the web and the plate 11, the cylinder 17, the gear 21 and the wheel 23 being frictionally driven as a result of such engagement. As the rear end of the plate 11 passes out of its engaging relation with the web, and therethrough with the makeready of the cylinder 17, the stop plate 33 is brought to the position occupied by the plate 32 in Fig. 1 and engages the anti-friction roller upon the stud 26 in the same manner as the plate 32 engages the stud 27. When coming to this position there is a free rolling action of the roller upon the stud within the socket 37 of the plate 33 with sufficient play to permit a continued frictional drive of the cylinder 17 until the plate 33 has reached the position described.

When the plate 33 has reached the position described, however, the friction drive of the cylinder 17 and the rotation of the wheel 23, as a result of such frictional drive, is positively stopped by the plate 33, and any slight overrunning of the cylinder 17 from moving inertia is prevented.

The gear 21 is thus brought to a fixed, predetermined position in relation to the gear 20 and receives movement solely from the plate 33 until there has been a proper adjustment of the gears 20 and 21, which adjustment may have been lost as a result of the drive of the gear 21 from the impression cylinder or D-roll 17. This action, however, is merely momentary, since with the restoration of the adjustment of the gears 20 and 21 a positive drive is imparted to the gear 21 by the gear 20 until the stud 27 enters the socket 37 in the succeeding plate 34 of the pair 33 and 34. If, during this short movement of the

gears 20 and 21, there is any departure from the desired adjustment, this is corrected as a result of the engagement of the stud 27 with the socket 37 of the plate 34.

5 Immediately following the plate 34 reaching the position occupied by the plate 32 in Fig. 1, the drive of the impression cylinder or D-roll 17 is under the control of the plate 34 for a very short interval, but sufficient to 10 ensure the engagement of the makeready of the cylinder 17 with the plate 12 upon the cylinder 10, whereupon the full friction drive of the cylinder 17 is initiated.

It will thus be noted that following the 15 making of each impression, the impression cylinder or D-roll is placed under the control of a stop plate such as 31, 33 or 35 for a sufficient interval to accomplish the readjustment of the gears 20 and 21, and that immediately preceding the making of the following impression, said impression cylinder or D-roll is placed under the control of a starting plate 32, 34 or 36 in a manner to ensure an angular speed of the impression 25 cylinder or D-roll corresponding with the angular speed of a plate upon the plate cylinder 10 for a sufficient interval to ensure a proper initial engagement of the paper between a plate and the cylinder 17.

30 By reason of the construction and arrangement of the studs 26 and 27 and the stop and start plates, substantially no wear such as gear teeth are subjected to occurs upon these cooperating members, so that the machine 35 may be operated for long intervals without possibility of any substantial loss of adjustment.

There is sufficient clearance between the 40 studs 26 and 27 and the sockets 37 of the plates of each pair to permit of the successive operation of the respective plates of each pair, in the manner above described, without interference from the other plate.

The adjustability of the studs and of the 45 various stop and start plates is merely for the purpose of securing great nicety in the positioning of the stop and start plates with relation to the steel plates upon the cylinder 10, and a proper positioning of the studs in 50 accord with any adjustment of the stop and start plates. Ordinarily, plates of the same size are used at the same time upon the cylinder 10 so that adjustment of the stop and start plates, to adapt the machine to slight 55 variation in the dimensions of the different plates, is not required, although it is possible. If adjustment be required, the position of the stop and start plates and the co-operating studs is such as to permit convenient access thereto.

60 While the mechanisms herein described were primarily designed for use upon a web printing machine, it is obvious that the same construction may be advantageously used 65 when printing upon separate sheets.

It is not my intention to limit the invention to the precise details of construction and combination of parts shown in the drawing, it being apparent that such may be varied without departing from the spirit and 70 scope of the invention.

Having described the invention, what I claim as new and desire to have protected by Letters Patent, is:—

1. A rotary web undersurface printing 75 machine embodying therein a printing couple consisting of an impression cylinder or D-roll, a plate cylinder adapted to receive a plurality of plates in spaced relation to each other, co-operating gears upon said impression cylinder or D-roll and upon said plate cylinder, said gears permitting slight variation in the angular speed of said impression cylinder or D-roll during the making of an impression, and co-operating means carried 80 by said impression cylinder or D-roll and by said plate cylinder, whereby the impression cylinder or D-roll is brought into a definite relation to the plate cylinder upon the completion of the making of each impression 85 and immediately prior to the initiation of the making of the succeeding impression.

2. A rotary web undersurface printing 90 machine embodying therein a printing couple 95 consisting of an impression cylinder or D-roll, a plate cylinder adapted to receive a plurality of plates in spaced relation to each other, co-operating gears upon said impression cylinder or D-roll and upon said plate cylinder, said gears permitting slight variation 100 in the angular speed of said impression cylinder or D-roll during the making of an impression, spaced studs upon said impression cylinder or D-roll, and spaced plates 105 upon said plate cylinder, said plates respectively having a socket adapted to co-operate with one of said studs, the socket of one of said plates being positioned adjacent the rear edge of an engraved plate upon the plate cylinder, and the socket upon the other plate 110 cylinder, and the socket upon the other plate being positioned adjacent the forward edge of the succeeding plate upon said cylinder, whereby the impression cylinder or D-roll is brought into a definite relation to the plate cylinder upon the completion of the making 115 of each impression and immediately prior to the initiation of the making of the succeeding impression.

3. A rotary web undersurface printing 120 machine embodying therein a printing couple 125 consisting of an impression cylinder or D-roll, a plate cylinder adapted to receive a plurality of plates in spaced relation to each other, co-operating gears upon said impression cylinder or D-roll and upon said plate cylinder, said gears permitting slight variation in the angular speed of said impression cylinder or D-roll during the making 130 of an impression, spaced studs upon said impression cylinder or D-roll, and spaced 135

plates upon said plate cylinder, said plates respectively having a socket adapted to co-operate with one of said studs, said socket being enlarged at the mouth thereof to ensure only momentary corrective action, the socket of one of said plates being positioned adjacent the rear edge of an engraved plate upon the plate cylinder, and the socket upon the other plate being positioned adjacent the forward edge of the succeeding plate upon said cylinder, whereby the impression cylinder or D-roll is brought into a definite relation to the plate cylinder upon the completion of the making of each impression and immediately prior to the initiation of the making of the succeeding impression.

4. A rotary web undersurface printing machine embodying therein a printing couple consisting of an impression cylinder or D-roll, a plate cylinder adapted to receive a plurality of plates in spaced relation to each other, co-operating gears upon said impression cylinder or D-roll and upon said plate cylinder, said gears permitting slight variation in the angular speed of said impression cylinder or D-roll during the making of an impression, spaced studs mounted for circumferential adjustment upon said impression cylinder or D-roll, and spaced plates mounted for circumferential adjustment upon said plate cylinder, said plates respectively having a socket adapted to co-operate with one of said studs, the socket of one of said plates being positioned adjacent the rear edge of an engraved plate upon the plate cylinder, and the socket upon the other plate being positioned adjacent the forward edge of the succeeding plate upon said cylinder, whereby the impression cylinder or D-roll is brought into a definite relation to the plate cylinder upon the completion of the making of each impression and immediately prior to the initiation of the making of the succeeding impression.

5. A rotary web undersurface printing machine embodying therein a printing couple consisting of an impression cylinder or D-roll, a plate cylinder adapted to receive a plurality of plates in spaced relation to each other, co-operating gears upon said impression cylinder or D-roll and upon said plate cylinder, said gears permitting slight variation in the angular speed of said impression cylinder or D-roll during the making of an impression, a wheel carried by the arbor of said impression cylinder or D-roll, spaced studs carried by said wheel, said studs being positioned in alinement with the teeth of the gear upon said impression cylinder or D-roll, and spaced socket plates carried by and mounted for circumferential adjustment upon the gear upon the plate cylinder co-operating with the gear upon the impression cylinder or D-roll, said plates respectively having a socket adapted to co-operate with one of said studs, the socket of one of said plates being positioned adjacent the rear edge of an engraved plate upon the plate cylinder, and the socket upon the other plate being positioned adjacent the forward edge of the succeeding plate upon said cylinder, whereby the impression cylinder or D-roll is brought into a definite relation to the plate cylinder upon the completion of the making of each impression and immediately prior to the initiation of the making of the succeeding impression.

tioned adjacent the rear edge of an engraved plate upon the plate cylinder, and the socket upon the other plate being positioned adjacent the forward edge of the succeeding plate upon said cylinder, whereby the impression cylinder or D-roll is brought into a definite relation to the plate cylinder upon the completion of the making of each impression and immediately prior to the initiation of the making of the succeeding impression.

6. A rotary web undersurface printing machine embodying therein a printing couple consisting of an impression cylinder or D-roll, a plate cylinder adapted to receive a plurality of plates in spaced relation to each other, co-operating gears upon said impression cylinder or D-roll and upon said plate cylinder, said gears permitting slight variation in the angular speed of said impression cylinder or D-roll during the making of an impression, a wheel carried by the arbor of said impression cylinder or D-roll, spaced studs carried by and mounted for circumferential adjustment upon said wheel, said studs being positioned in alinement with the teeth of the gear upon said impression cylinder or D-roll, and spaced socket plates carried by and mounted for circumferential adjustment upon the gear upon the plate cylinder co-operating with the gear upon the impression cylinder or D-roll, said plates respectively having a socket adapted to co-operate with one of said studs, the socket of one of said plates being positioned adjacent the rear edge of an engraved plate upon the plate cylinder, and the socket upon the other plate being positioned adjacent the forward edge of the succeeding plate upon said cylinder, whereby the impression cylinder or D-roll is brought into a definite relation to the plate cylinder upon the completion of the making of each impression and immediately prior to the initiation of the making of the succeeding impression.

In witness whereof I have hereunto affixed my signature, this 19th day of December, 1930.

ALBERT S. WEBSTER.
